UNITED STATES PATENT OFFICE.

JOHN W. RINGER, OF CASTLETON, INDIANA.

AUTOMATIC ELECTRIC-STORING DEVICE.

No. 870,688.

Specification of Letters Patent.

Patented Nov. 12, 1907.

Application filed July 17, 1906. Serial No. 326,652.

To all whom it may concern:

Be it known that I, JOHN W. RINGER, a citizen of the United States, residing at Castleton, in the county of Marion and State of Indiana, have invented certain 5 new and useful Improvements in Automatic Electric-Storing Devices, of which the following is a specification.

This invention relates to a device for generating and storing electricity, by means of a mill operated by the 10 wind, and the object of the invention is to provide a device which will operate at any time, day or night, whenever the wind arrives at such a velocity as to operate the mechanism for generating the current.

The object consists further in a generating and storing 15 device of electricity which is operated by a mill which is operated by the wind, and having therein a means for generating and storing the electric current so that the same will be at hand whenever its application or use is desired.

20 A device of this character embodying the several features to carry out my invention is illustrated in the accompanying drawings, in which

Figure 1 is a side elevation of a device for generating and storing electricity embodying the several features of 25 my invention. Fig. 2 is a top or plan view of the construction shown in Fig. 1, except that the storage cells have been omitted. Fig. 3 is a rear elevation of the disk-wheel showing the means for shifting the driving mechanism for said disk, with the other mechanism omitted.

30 Fig. 4 is a front elevation of the disk-wheel showing the spring for returning said disk to its initial position. Fig. 5 is a fragmentary detail sectional view showing the manner in which the ball and socket joint is formed between the governor-shaft and its connecting link. Fig. 6 is 35 a detail in plan view of the disk-wheel and the associated parts for operating same, on an enlarged scale. Fig. 7 is a perspective view of the rear surface of the disk 3 and the associated parts for operating said wheel. Fig. 8 is a fragmentary detail view in section showing

40 the manner in which the driving sleeve is splined to the driving shaft. Fig. 9 is a diagrammatic view of the electrical connections showing all the parts in their initial position, and showing the movable arm, by means of the dotted lines, in an advanced position.

45 Fig. 10 is a view similar to Fig. 9 except that the movable disk-wheel and the movable arm are shown to be occupying an advanced position with relation to the stationary face plate, and by means of the dotted position, the movable arm is shown in a still further advanced position.

In the drawings, 1 is a platform or base on which the mechanism of the device is mounted. 2 is a face-plate mounted in a perpendicular manner and is rigidly secured to the base 1. Mounted parallel with the face-

plate 2 and in the rear thereof is a movable disk-wheel 55 3 suitably mounted in a standard 4 which rests on the base 1, and its object will be hereinafter described.

The device is provided with a dynamo 6 for generating the current. The armature shaft of the dynamo 6 is provided at one end with a pulley 7, and by means 60 of a belt or chain the same is connected with any suitable power generator. As my device is more particularly designed for rural use, I prefer in that instance to connect the dynamo 6 with a windmill, so that the cost of deriving the initial power will be of small consequence, after the mill has once been erected.

The device is also provided with a series of storage batteries 10, of any old and well-known character, so that the current when generated will be confined and taken care of until such time when it is desired to use 70 same. The mechanism employed and the manner in which the batteries are charged is one of the chief objects of this invention, and the same will now be described.

The face-plate 2 of the device is provided with a 75 horizontally extending and centrally located shaft 15, having rigidly secured thereto an arm 16, which extends across the face of said plate and in a parallel manner therewith. The arm 16 is susceptible to a rocking movement, which movement is on a curvilinear plane, 80 and as the end of said arm carries a pin 17 which extends transversely thereto, the face-plate 2 on a part of its edge is cut on a circle concentric with the shaft 15, so that the course of travel of the pin 17 on the arm 16 will be free from obstruction. The arm 16 is actuated by means of a connecting link 18 which is pivotally connected to said arm at 19, and the link 18 pivotally connects at its other end with a vertically movable governor-shaft 20 at 21. As the governor-shaft is susceptible of a revolving movement as well as a vertical 90 movement, a ball and socket joint 21 between said shaft and the link 18 becomes necessary. The rotation of the governor-shaft 20 is secured by passing said shaft through a hollow casing or tube 22, having its upper end bifurcated to form a yoke 23, to which the governor 95 arms are pivoted. The casing 22 is provided with a pinion 25 which is rigidly secured thereto. The pinion 25 is held into position by means of a standard 26 which is secured to the face-plate 2. The pinion 25 meshes with a pinion 27 which is mounted on the vertical shaft 28, which stands parallel with the governor-shaft 20. The shaft 28, on its lower end, is provided with a bevel pinion 29 which meshes with a corresponding pinion 30, secured to the armature shaft of the dynamo 6.

100 I will be seen that the dynamo 6 performs a double function, first, that of generating the electric current, the disposition of which will be hereinafter described,

105

and second, that of imparting rotation or movement to the governor-shaft 20, through the pinions 29 and 30, vertical shaft 28 and the pinions 27 and 25.

It will be readily understood, as the speed and rotation of the dynamo 6 increases, the rotation of the governor-shaft is correspondingly increased, and as the centrifugal action causes an outward movement of the governor balls, which is old and well-known, the governor-shaft 20 is depressed. This downward movement of the shaft 20 causes the arm 16 to travel in an arc across the face of the plate 2. The object of this movement will be hereinafter described.

The face-plate 2 is provided with a series of pins or plugs 45 that extend transversely through said plate. 15 The number of these plugs that extend through said plate correspond to the number of the cells 10 employed, and an extra plug 46 is provided which is positioned on the rear side of the plate 2 but does not pass through to the surface, and does not come into contact 20 with the arm 16, so that a short circuit is prevented when the arm stands in open or initial position. The plug 46 is connected directly with the dynamo 6 by means of the wire 52, and the wire 51 connects with one of the brushes 60 to the first one of the series of cells 10. 25 The arm 16 is connected directly with the dynamo 6 by means of the wire 54. As the speed of the dynamo 6 increases, a corresponding increased volume of current tends to flow, and I have provided means to prevent the increase in volume, and to prevent loss. With this 30 increased speed of the dynamo the rotation of the governor is also increased, which as heretofore mentioned, will depress the governor-shaft 20 and cause the arm 16 to move across the plugs 45. At each contact of the arm 16 with one of the plugs 45 on its forward movement, a cell 10 is brought into the circuit so that, as the volume of the current tends to increase, a greater number of the cells are within the circuit.

It will be understood that the number of cells within the circuit are at all times sufficient to keep the current 40 at the required value. Should the wind decrease in pressure, causing a lower rotation of the dynamo and consequently a reduced voltage of current generated, the arm 16 will settle back, thereby reducing the number of cells that are in the circuit. So it will be seen 45 that the arm 16 compensates for the fluctuation of the current. The mechanism is so timed that the voltage has risen sufficiently to overcome the resistance of the first cell before the arm 16 reaches the first plug 45, and further, the voltage is greater than the combined resistance of two cells before the arm reaches the second plug 45, and so on as the arm advances. Suppose, however, that the pressure of the wind is sufficient merely to raise the arm 16 to the first plug 45, and remain so for a time. The first cell would in this case alone be affected, and 50 would receive the entire amount of the current generated, as determined by the resistance of the cell, while the remaining cells would receive nothing. To prevent any loss of current I provide means for bringing each cell into the circuit and having them uniformly charged with the amount of current generated, as determined by the resistance of the cells, and the means for bringing all said cells into the circuit when the arm 16 stands stationary, will now be described.

The disk-wheel 3 is provided with a series of brushes

60 which extend horizontally and are arranged in a semi-circle thereon, and the ends of the brushes contact the inner ends of the plugs 45 when the disk-wheel is operated. There is a brush 60 for each plug 45 and also a brush 60 for the plug 46. Each brush is connected with one of the cells by means of a wire 65, so that all 70 the cells are connected with the disk-wheel 3.

The movement of the disk-wheel consists of a partial rotation which is secured by means of a pinion 35, secured to the governor-shaft casing 22, and is held in position by means of the standard 26 in the same manner 75 as the pinion 25. The pinion 35 meshes with a corresponding pinion 36, secured to the vertical shaft 37, and the latter carries the bevel pinion 40 on its lower end. The pinion 40 meshes with a corresponding pinion 41 mounted on the horizontal shaft 48, the latter being 80 suitably supported in the face-plate 2. The shaft 48 is provided with a pinion 50 which is loosely mounted thereon and engages the teeth on the periphery of the disk-wheel 3. The pinion 50 is provided with a ratchet faced hub which engages a movable collar 95, which is 85 splined to the shaft 48 and has one of its ends provided with ratchet teeth to engage the teeth on the hub of the pinion 50, and it will be seen that when the governor-shaft 20 is operated, the disk-wheel 3 will be moved forward through the gear wheels 35 and 36, the bevel 90 pinions 40 and 41, the shaft 48, the splined collar 95, and the pinion 50. The disk wheel 3 and the arm 16 may move simultaneously as when the speed is rising, and the arrangement is such that their normal movements will be in opposite directions. However, the 95 arm 16 may be stationary while the disk-wheel 3 is always moving unless the pinion 50 is out of gear. The greatest distance of travel of the disk-wheel 3 is sufficient to permit all of the brushes 60 to pass the plugs 45, at which point the disk will be thrown out of gear from 100 the driving mechanism and be returned to its initial position by means of a spring 70.

Arriving at its initial position the disk is immediately thrown into operation and again starts forward. The arm 16 trips the driving mechanism and disengages 105 it from the disk-wheel 3, so that the position of said arm determines the length of travel of said disk. As the arm changes its position according to the speed of the dynamo, the length of travel of said disk will vary. As all the brushes 60 normally stand engaged with the 110 plugs 45, it will be seen that the movement of the disk and the arm 16 will be such as to bring a sufficient number of cells 10 into the circuit to care for the voltage generated at any time. The disk-wheel 3 is provided with a throw-out device, and as the said disk 115 advances it moves the cells 10 in a numerical order into the circuit until said throw-out device comes into contact with the pin 17 mounted in the end of the arm 16, at which point the disengagement is effected. When the disk-wheel is disengaged it is immediately returned to its initial position by means of the spring 70 which engages the disk at one end and is secured to the shaft 71 at the other.

The driving means for rotating the disk-wheel 3 is thrown out and into engagement with said disk by a 125 single and positively moving device, consisting of a sleeve 75 loosely mounted on the shaft 71 and is provided with a plurality of annular grooves 76 and 77.

An L-shaped yoke 80 engages the groove 76, and said yoke is pivoted at 81 in the standards 82 which are secured to the disk-wheel 3. A bell crank 85 is pivotally secured at 86 to the disk-wheel 3, one end of said crank extending beyond the periphery of said disk and into the path of the pin 17, mounted in the end of the arm 16. A link 87 connects the lower end of the bell crank 85 with the yoke 80, and by imparting a reciprocating movement to the bell crank 85, the sleeve 75 may longitudinally be moved on the shaft 71. This movement of the sleeve is only desired to impart a rocking movement to a second yoke 90, which is pivotally mounted at 96 in a standard 97, which standard extends to and is secured to the base 1. One end of the yoke 90 engages the annular groove 77 in the sleeve 75, and extends to and engages at its opposite end with an annular groove 93 in the collar 95 which is provided with a ratchet face and is splined to the shaft 48. When the bell crank 85 is given a reciprocating movement, the collar 95 will be moved longitudinally on the shaft 48 into or out of engagement with the ratchet-faced hub on the pinion 50, heretofore described. When the bell crank 85 thus engages the pin 17 on the forward movement of the disk-wheel 3, said crank is forced backward, which, through the intermediate mechanism, disengages the collar 95 from the pinion 50. The spring 70 having been tightened during the forward movement of the disk-wheel 3 will readily return said disk to its initial position when the latter is disengaged from its driving means. At the moment the disk-wheel 3 reaches its initial position, the bell crank 85 engages a fixed arm 100, thus reversing the movement of said crank which throws the collar 95 into engagement with the pinion 50, thus compelling the disk-wheel 3 to again move forward. The disk-wheel then moves until the bell crank again engages the pin 17 when the parts are again disconnected, so that this intermittent movement is repeatedly carried forward until those cells that are within the circuit are charged to their utmost capacity at which time the mechanism may be permitted to rest.

It will be noted that all the cells may not necessarily be charged, but that at least some current is stored whenever sufficient wind blows to operate the device. I may also state at the time of starting the device that should the wind be of such high pressure as to force the arm 16 to the limit of its travel, it will force the disk-wheel 3 back to its initial position, after contacting the bell crank 85 to disengage the driving means, and will hold the said disk in its initial position until the wind has subsided. During this period of time all of the cells 10 will be within the circuit and be simultaneously and uniformly charged. The line wires leading from the cells are designated as 105 and 106.

Having thus fully described my said invention, what I desire to secure by Letters Patent, is—

1. In a device of the character described comprising a fixed face-plate, a pivotally mounted movable means on said face-plate, a disk wheel movably mounted in a parallel plane with the face-plate, means for operating said disk wheel, a series of contacting plugs mounted on both the face-plate and disk wheel, a series of cells connected with the plugs on the disk wheel, a suitable electric generator connected with the pivotally mounted movable means, and means for operating the last-named means. 60

2. In a device of the character described comprising a fixed face-plate, a pivotally mounted movable means on said face-plate, a disk wheel movably mounted in a parallel plane with the face-plate, means for operating said disk wheel, a series of contacting plugs mounted on both the face-plate and disk wheel, a series of cells connected with the plugs on the disk wheel, a suitable electric generator connected with the pivotally mounted movable means and the cells, means for operating the pivotally mounted movable means, means for disengaging the driving means from the disk wheel, and means for returning the disk wheel to its initial position. 70

3. In a device of the character described comprising a fixed face-plate, an arm movably mounted on said face-plate, means for actuating said arm, a disk wheel mounted parallel with the face-plate and susceptible to a rocking movement, means for moving the disk wheel, a throw-out device on the disk wheel, trip means carried by the arm to engage and trip the throw-out device, means for returning the disk wheel to its initial position, and a stationary means to engage the throw-out device for moving the driving means into engagement with the disk wheel. 80

4. In a device of the character described comprising a fixed face-plate, an arm movably mounted on said face-plate, means for actuating said arm, a disk wheel mounted parallel with the face-plate and susceptible to a rocking movement, means for moving the disk wheel, a throw-out device on the disk wheel, trip means carried by the arm to engage and trip the throw-out device, means for returning the disk wheel to its initial position, a stationary means to engage the throw-out device for engaging the driving means with the disk wheel, a series of contacting plugs on both the face-plate and disk wheel, cells connecting with the plugs on the disk wheel, and an electric generator connecting with the movable arm and the cells. 90

5. In a device of the character described comprising a fixed face-plate, an arm movably mounted on said face-plate and adapted to move across its surface, a movable disk wheel mounted parallel with the face-plate, a series of contacting plugs carried by the face-plate and disk wheel, a series of cells connected with the plugs on the disk wheel, an electric generator connecting with the movable arm and the cells, a driving means for the disk wheel, throw-out means carried by the disk wheel to contact the movable arm for disengaging said driving means from the disk wheel, and a fixed stop device to contact the throw-out device for moving the driving means into engagement with the disk wheel. 100

In witness whereof, I, have hereunto set my hand and seal at Indianapolis, Indiana, this 28th day of June, A. D. one thousand nine hundred and six. 115
